SPEED REGULATING SYSTEM

Edgar D. Lilja, Rockford, Ill., assignor to Woodward Governor Company, Rockford, Ill., a corporation of Illinois

Application June 19, 1940, Serial No. 341,264

9 Claims. (Cl. 290—40)

This invention relates to speed regulating systems and more particularly to governors of the type which are equipped with hydraulic compensating or stabilizing mechanism to prevent hunting.

The primary object is to modify the action of such hydraulic compensating mechanism in a novel manner such as to produce closer regulation of the prime mover speed in spite of sudden load changes.

The invention also resides in the novel and simple character of the means employed to produce the modifying action.

Other objects and advantages of the invention will become apparent from the following detailed description taken in connection with the accompanying drawing, in which

Figure 1 is a schematic view and wiring diagram of a current generating system and governor control embodying the novel features of the present invention.

Figs. 2 and 3 are fragmentary views of modifications.

While the invention is susceptible of various modifications and alternative constructions, I have shown in the drawing and will herein describe in detail the preferred embodiment. It is to be understood, however, that I do not intend to limit the invention by such disclosure but aim to cover all modifications and alternative constructions falling within the spirit and scope of the invention as expressed in the appended claims.

In the illustrative embodiment shown in the drawing, the invention is incorporated in an hydraulic governor indicated generally at 5 for controlling the speed of a water-wheel turbine 6 actuating a generator 7 which supplies electric current to a network 8 on which a load 9 is imposed. As usual, the turbine speed is regulated by a penstock valve 10 which is adjusted, usually through intermediate hydraulic mechanism (not shown), with a rod 11 of a servomotor. Herein, the latter comprises a piston 12 mounted on the rod 11 and reciprocable in a cylinder 13 and preferably urged in the speed-decreasing direction by a compression spring 14.

The governor proper comprises a head 15 carrying flyballs 16 and driven from the turbine prime mover 6 through a connection indicated at 17. The flyballs are urged inwardly by a coiled spring 18 which may be adjusted through a screw 19 to vary the governor speed setting. The position of the flyballs determines the axial position of a pilot piston 20 with respect to a port 21

in a sleeve 22 which is slidable axially in a valve body 22a and has a port 23 communicating through a conduit 24 with an accumulator 25. The latter is charged with pressure fluid by a power driven pump 26. The lower end of the valve cylinder 28 communicates with an oil sump 29 through a port 30 and a passage 31. Pressure fluid flows to and from the upper end of the servo cylinder 13 through a passage 32 connected to the port 21.

The mechanism usually employed to compensate for the lag of the prime mover and of the control system so as to prevent hunting includes the sleeve 22 which carries a piston 33 reciprocable in a receiving cylinder 34 and urged by a spring 35 toward a neutral position. A transmitting piston 36 moves with the servo piston 12 to cause oil trapped in the lower end of the piston cylinder 37 to flow to and from the receiving cylinder 34 through a passage 38 having a leak port 39 therein adjustable by a needle 40. The valve chamber communicates with the sump 29 through a pipe 41.

The arrangement thus far described is typical of the compensating type of hydraulic governor controls to which the present invention is particularly applicable. In operation, an increase in the turbine speed causes the flyballs to move outwardly lifting the pilot piston 20 and permitting oil to escape to the sump from the servo cylinder through the ports 21 and 30 and the passages 32 and 31. This permits the spring 14 to move the speed controller 11 upwardly which causes closure of the valve 10 and a corresponding decrease in the turbine speed. As an incident to this movement of the servo and transmitter pistons 12 and 36, the pressure in the cylinders 34 and 37 is reduced permitting the piston 33 and the valve sleeve 22 to rise and follow-up the movement of the piston 20. Thus, the port 21 is covered slightly before the normal speed is again attained. Thereafter, oil from the sump 41 is drawn through the valve 39 gradually raising the compensating pressure and permitting lowering of the sleeve to normal position under the action of the centering spring 35.

In response to a decrease in speed, the piston 20 is lowered admitting high pressure fluid from the accumulator to the servo cylinder 13 so as to lower the control rod 11 against the action of the spring 14 and increase the turbine speed. This results in an increase in the compensating pressure and immediate lowering of the valve sleeve 22 to close the port 21, gradual restoration

of the sleeve to normal position being effected by leakage of fluid to the sump through the valve 39.

The present invention contemplates the provision of simple means to detect sudden load changes and operates in a novel way through the anti-hunting mechanism above described to produce a valve action anticipatory of the speed changes which would normally occur whereby to reduce the prime mover surges usually incident to sudden load changes. The supplementary compensating means includes an hydraulic actuator 42 connected in the fluid compensating circuit and operable to vary the pressure therein instantaneously in response to load changes. The actuator herein shown comprises a third cylinder 43 the head of which leads to the compensating chamber through a passage 44, the connection being to the cylinder 37 in the present instance. A piston 45 in the cylinder 43 is urged in a pressure increasing direction by a spring 46 and the piston rod 47 is connected to an electric actuator 48 the energization of which varies with changes in the load on the generating system. In Fig. 1, the actuator comprises an armature 49 on the piston rod coacting with a solenoid coil 50 which is connected to the secondary of a transformer 51 having its primary interposed in one of the lines leading from the generator 7 so as to be energized constantly. The spring and solenoid are of such construction that the piston 45 occupies a different position for each value of generator load from no load to full load and that the piston position is not influenced appreciably by independent changes in the position of the servo piston 12. In a direct current system (see Fig. 2), a shunt 51 is interposed in one of the supply lines, the voltage across the shunt being impressed on the solenoid.

Assuming the parts to be in equilibrium, as shown in Fig. 1, the load compensating control produces its anticipating corrective action in the following manner in response to a sudden increase in load. This results in a corresponding increase in the current energizing the solenoid coil 50 drawing the plunger 49 downwardly against the compression of the spring 46. Such movement of the piston 45 draws oil out of the transmitting cylinder 37 and the consequent lowering of the pressure in the receiving cylinder 34 permits the valve sleeve 22 to rise relative to the valve piston 20. Pressure fluid thus flows from the accumulator 25 into the power cylinder 13 and the servo piston 12 moves downwardly so as to start increasing the speed of the prime mover before the fly-balls have detected a drop in speed.

The reverse action occurs upon a sudden decrease in load which causes the pull of the solenoid 50 to be decreased and the piston 45 to move upwardly under the action of the spring 46. Oil is thus forced into the compensating system and the piston 33 is forced downwardly so as to permit the passage of oil from the power cylinder 13 to the sump. The spring 14 then moves the control rod 11 in the speed-decreasing direction in anticipation of the speed change that would normally result from the load reduction.

It will be observed that the load compensator produces the same action of the governor pilot valve as the flyballs would produce in the absence of the load detector. This action occurs in advance of the time that the flyball action would otherwise occur and therefore is of anticipa-

tory character so as to compensate for the inherent lag in the response of the governor and reduce surges of the prime mover that normally take place under sudden load changes. The load compensator in effect supplements the regular governor control which operates in the normal way to correct for gradual speed changes. Owing to the leakage through the valve 39 following the pressure changes instituted by the electric load change detector, the action of the latter is of temporary character and does not produce a permanent shift in the control point of the governor.

The load compensating mechanism described above is also provided with means for adjusting the amount of compensation. To this end, a rheostat 53 is connected in parallel with the secondary of transformer 51 or, in the case of the DC system, in series with the solenoid. By adjustment of this rheostat, the change in energization of the electric actuator 48 for a given load change may be varied as desired. By opening a switch 54, the load compensator may be disabled completely.

As shown in Fig. 3, the electric load compensating actuator may take the form of a torque motor 55 geared to rack teeth on the piston rod 47, preferably through the medium of a worm 56 on the motor shaft meshing with a worm wheel 57 on the pinion wheel. A spring 58 acts on the motor shaft in opposition to the motor. As before, a decrease in the load current decreases the motor torque permitting the piston 45 to move upwardly and assume a different position for each load condition. For some installations, this modification is advantageous since it facilitates the addition of inertia which may be proportioned to delay the load compensating action to suit given operating conditions and prime mover characteristics. Also, the worm gearing is self-locking so that the motor is not influenced by pressure changes in the cylinder 43 due to independent movements of the servo piston.

It will be observed from the foregoing that the load compensating action is effected hydraulically through the intermediary of the compensating mechanism regularly employed to prevent hunting. In this way, the mechanism required to effect the anticipating adjustment is extremely simple in construction, reliable in operation, and readily adaptable to a given installation.

I claim as my invention:

1. A system for regulating the speed of a prime mover driving an electric generator having, in combination, an hydraulic servo motor regulating the speed of said prime mover, a source of pressure fluid, a pilot valve controlling the flow of said fluid to and from said servo motor and including two axially movable valve elements, flyballs driven in unison with said prime mover and modulating one of said valve elements in accordance with speed changes, interconnected cylinders filled with fluid and connected to a body of fluid through a leak valve, a transmitting piston in one of said cylinders actuated by said servo motor, a receiving piston in the other cylinder connected to said other valve element to produce a compensating action, a third fluid filled cylinder communicating with said first mentioned cylinders and having a piston urged in a direction to vary the pressure in the cylinders, and an electric actuator constantly but variably energized from the network supplied by said gen-

erator and controlling the position of said third piston in accordance with load variations.

2. A system for regulating the speed of a prime mover driving an electric generator having, in combination, an hydraulic servo motor regulating the speed of said prime mover, a source of pressure fluid, a pilot valve controlling the flow of said fluid to and from said servo motor and including two axially movable valve elements, means responsive to the speed of said prime mover and modulating one of said valve elements, interconnected cylinders filled with fluid and connected to a fluid source through a leak valve, a transmitting piston in one of said cylinders actuated by said servo motor, a receiving piston in a second cylinder connected to said other valve element to produce a compensating action, a third fluid filled cylinder communicating with said first mentioned cylinders and having a piston urged in one direction, and an electric actuator constantly but variably energized from the network supplied by said generator and operable to cause modulation of the position of said third piston in accordance with load variations.

3. The combination with a prime mover and an electric generator driven thereby of, an hydraulic governor operable in unison with said prime mover and having a speed responsive servo motor modulating the speed of said prime mover, hydraulic compensating mechanism energized in response to operation of said servo motor and operable to impart a compensating adjustment to said governor whereby to prevent hunting, an electric actuator variably energized in accordance with changes in the load on said generator, and means operated by said actuator to cause variations in the hydraulic pressure in said mechanism and thereby produce a supplemental adjustment of said governor compensating for sudden load changes.

4. The combination with a prime mover and an electric generator driven thereby of, an hydraulic governor operable in unison with said prime mover and having a speed responsive valve and servo motor controlled thereby and modulating the speed of said prime mover, hydraulic compensating mechanism energized in response to operation of said servo motor and operable to impart a compensating adjustment to said valve whereby to prevent hunting, an electric actuator variably energized in accordance with changes in the load on said generator, and means operated by said actuator to vary the hydraulic pressure in said mechanism and thereby produce a supplemental adjustment of said valve.

5. The combination with a prime mover of, an hydraulic governor operable in unison with said prime mover and having a speed responsive

valve and servomotor modulating the speed of said prime mover, hydraulically connected transmitting and receiving cylinders having a leak valve outlet and pistons therein respectively connected to said servomotor and said valve so as to impart a compensating adjustment to said valve as an incident to speed adjustment of said prime mover, actuator variably energized in accordance with changes in the load on said prime mover, and a third cylinder communicating with said cylinders and having a piston variably positioned by said actuator.

6. The combination with a prime mover and an electric generator driven thereby of, a governor driven in unison with said prime mover and operable to modulate the speed thereof, hydraulic mechanism associated with said governor to impart a compensating adjustment thereto and prevent hunting, an electric actuator variably energized in accordance with changes in the load on said generator, means operated by said actuator to vary the hydraulic pressure in said mechanism, and means for varying the degree of energization of said actuator in accordance with the load on the generator.

7. The combination with a prime mover of a governor operable in unison with and controlling the speed of said prime mover, an hydraulic system associated with said governor to produce a compensating action in response to speed adjustments, and means operable in response to changes in the load on said prime mover to produce corresponding pressure changes in said hydraulic system.

8. The combination with a prime mover of a governor operable in unison with and controlling the speed of said prime mover, an hydraulic system associated with said governor to produce a compensating action in response to speed adjustments, an hydraulic cylinder communicating with said hydraulic system and having a piston therein constantly urged in one direction, and means operable automatically to vary the position of said piston in accordance with load changes imposed on said prime mover.

9. The combination with a prime mover of a governor operable in unison with and controlling the speed of said prime mover, an hydraulic system associated with said governor to produce a compensating action in response to speed changes, an hydraulic cylinder communicating with said hydraulic system and having a piston therein constantly urged in one direction, and means opposing the movement of said piston including an electric actuator constantly energized to a degree corresponding to the load imposed on said prime mover.

EDGAR D. LILJA.
